Billion & Armitage(57) CLAIM

The ornamental design for a combined golf bag and banner, as shown and described.

DESCRIPTION

FIG. 1 is a perspective view of a combined golf bag and banner showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showings in the FIGS. are for environment and form no part of the claimed design.
